CLAIM

The ornamental design for a sucker rod string rotator with position indicator, as shown and described.

DESCRIPTION

FIG. 1 is a perspective view of a sucker rod string rotator with position indicator showing our new design with the position indicator in an aligned position.

FIG. 2 is a front elevational view thereof.

FIG. 3 is a rear elevational view thereof.

FIG. 4 is a side elevational view thereof.

FIG. 5 is a side elevational view of a side opposite that shown in FIG. 4.

FIG. 6 is a top plan view thereof.

FIG. 7 is a bottom plan view thereof; and,

FIG. 8 is a perspective view of the sucker rod string rotator of FIG. 1 showing our new design with the position indicator in a non-aligned position.

The broken lines in the drawings are for the purpose of illustrating environment only and form no part of the claimed design. The cross-hatching indicates contrast in color with adjacent portions of the sucker rod string rotator with position indicator that are not cross-hatched, and no particular color is claimed.
